UNITED STATES PATENT OFFICE.

THOMAS HILL, OF CHICAGO, ILLINOIS.

DESIGN FOR AN ORGAN-CASE.

SPECIFICATION forming part of Design No. 15,037, dated June 3, 1884.

Application filed March 25, 1884. Term of patent 3½ years.

To all whom it may concern:

Be it known that I, THOMAS HILL, a subject of the Queen of England, residing at Chicago, in the county of Cook and State of Illinois, have invented certain new and useful Designs for Organ-Cases, of which the following is a specification, reference being had therein to the accompanying drawings.

My invention relates to a design for organ-cases. For the details of the invention reference is made to the accompanying illustration, wherein all the features are clearly portrayed.

The main features of the design are the central and side arched-shaped projections, A and B B, upon the upper edge of the back, each being ornamented with suitable engraved lines, a and b b, and the side arches, B B, being suitably scalloped, as shown at c. Below each projection B is a panel, C, ornamented with engraved lines d, as shown, while a central panel, D, suitably ornamented, shows the back of a book-receptacle, which consists of side pieces, e, and front pieces, E, said front piece being ornamented, as shown. Below

piece E is a music-shelf, F, ornamented with engraved lines f, and upon each side thereof a suitably-ornamented panel, G. Upon each side edge of the top there is an upright, H, irregular in outlines, as shown, and each ornamented by an ornamental knob, g.

What I claim is—

1. The design for organ-cases herein shown.
2. In an organ-case, the design for the top of the same, consisting of the configuration and ornamentation of the parts A B B, as 35 shown.
3. In an organ-case, the design for panels C D and piece E, the same consisting of the configuration and ornamentation shown.
4. In an organ-case, the design for side uprights, H, the same consisting of the configuration and ornamentation shown.
